UNITED STATES PATENT OFFICE.

JOHN ALLEN HEANY, OF NEW HAVEN, CONNECTICUT, ASSIGNEE TO HEANY LABORATORIES, INC., OF NEW HAVEN, CONNECTICUT, A CORPORATION OF CONNECTICUT.

EIGHTEEN YEARS.

Application filed August 2, 1921, Serial No. 430,156. Renewed March 24, 1926.

This invention relates to an ignition device for internal combustion engines having inherently self-regulating features due to a combination of normal battery voltage, charging battery voltage, intake cooling and explosion heating, and replacing on the engine all the usual apparatus required in conjunction with the ordinary type of spark ignition covering timing gears, spark coil, distributor, circuit breaker, condenser and high tension wiring.

The ignition element consists primarily of an electric conductor to be heated by low voltage direct current, so constructed that the upper portion has a more concentrated heating section than the lower portion so that at low voltage only the upper portion is heated and as the voltage increases the element continues to become heated to an ignition temperature toward the lower portion.

The fundamental principle of my igniting element is that of employing an elongated metal member, adapted and connected to be heated by an electric current passing therethrough for the purpose of firing the charges in the cylinder. This element obviously becomes heated throughout its length, and owing to its peculiar form is first and more intensely heated at one end than the other, and also gradually becomes hotter throughout its length, by increased voltage. This ignition element may be formed of a single piece of tapered wire or rod, supported at its opposite ends within the tube or casing and having its smaller end positioned within the closed end of the tube while the larger end is adjacent the cylinder in which the tube or plug is positioned.

I prefer, however, to form this ignition element of a relatively long strand of fine wire which is wound to form a tapered coil of gradually increasing pitch towards its lower end so that the windings are spaced further apart at said lower end and if desired it may be specially wound to form a helical coil which is also more closely wound at one end than the other and said windings gradually increasing towards the lower end. These coils may be mounted free and self-supporting except for their end connections as shown in the drawings and as will be later more specifically referred to or may be provided with a support of suitable character as will be again referred to.

With these and other objects in view the invention resides and consists in the construction and novel combination and arrangement of parts hereinafter more fully described, illustrated in the accompanying drawings, and pointed out in the claims hereto appended, it being understood that various changes in the form, proportion, size and minor details of construction within the scope of the claims may be resorted to without departure from the spirit or sacrificing any of the advantages of the invention.

Similar characters of reference denote like or corresponding parts throughout the several figures of the accompanying drawings forming a part of this specification, and to upon which.

Fig. 1 shows a sectional elevation of an ignition element formed in accordance with the particulars of my invention and mounted in a tubular casing resembling in appearance a commercial form of spark plug;

Fig. 2 is a sectional elevation showing a form of my invention, comprising a single length of wire, the opposite ends of which are supported from a tube in which it is mounted;

Fig. 3 is an enlarged view of the element formed as in Fig. 1 of a piece of fine wire wound to form a long coil, the smaller windings at one end being closer together than the larger windings at the opposite end;

Fig. 4 shows a similar sectional view, of a modified form of wound wire element, the same being of equal diameter throughout its length but the windings being closer together at one end than the other;

Figs. 5, 6, 7 and 8 show wire elements which are similar in formation to that shown in Fig. 4, in that the coil is of the same diameter throughout the length and that the windings are closer together at the upper end than at the lower. These figures also show special means for supporting the wound wire ignition element as will later be again referred to; and

Fig. 9 shows a diagrammatical illustration of four of the ignition elements connected up in a series and mounted in a four cylinder engine block.

The fundamental principle of the ignition element is that of a tapered wire of small section, preferably mounted in a tube or casing which in turn is inserted for use in a

cylinder, in somewhat the same manner as the ordinary spark plug, but does not produce a jump spark. It is constructed along much simpler lines and obviously operates in a different manner by having different portions throughout its length heated sufficient to fire a charge in a cylinder, at different positions of the stroke of the pistons.

With an engine at rest the usual battery voltage is approximately 5.5 volts and when applied in use to my ignition element at this voltage, only a small portion near the top of the element would be heated to ignition temperature and whereby an explosion would not occur until the compressed fresh charge reached almost to the top of the pocket in the tube. As the generator commences to charge, the voltage would rise to approximately 6.5 volts and the increased current due to this higher voltage would heat the ignition element approximately to the middle. Higher engine speed corresponding to ordinary running conditions would give a charging voltage of approximately 7.5 volts and at this voltage the extreme lower end would be heated to an igniting temperature. The lower end of the igniting element is kept some distance back from the opening into the cylinder so as to insure some compression taking place before firing.

Referring in detail to the characters of reference marked upon the drawing, 10 represents a tubular body member having a central cylindrical longitudinal pocket 11 formed therein to receive the ignition element 12 and 12' which is of a general elongated formation and mounted centrally within the pocket. The upper end of said element being supported as at 13 through an insulator member 14, by a wire or conducting rod 15 mounted in said insulation and whose upper end may be threaded as at 16 shown in Fig. 1, for the attachment of a binding nut, not shown. The lower end of the ignition element may be secured in any suitable manner by a metal connection 17 with the lower portion of the tubular body 10 in a manner to pass the current through the element and body. The lower peripheral portion of the body may be threaded as shown at 18 for positioning in the tapped hole of a cylinder in which it is to be employed.

As before stated the particular form of construction of the tubular body in which my element is mounted does not necessarily form any material part of my present invention. For convenience, however, this body should be adapted for removable attachment in the cylinder heads of a motor and may otherwise be made to resemble so far as the outer appearance is concerned, any form of spark plug body adapted to accommodate my improved element. The element

proper as shown in the several drawings is made of suitable material and particularly formed and shaped so that the upper portion will have a more concentrated heating section than the intermediate or lower portion and so that an electrical current passing therethrough will first bring about the heating of said upper section and then the heating of the intermediate and lower sections as the voltage increases.

In Figs. 1 to 4 inclusive the ignition elements 12 and 12' are shown supported at their opposite ends only and the rigidity of the wire coil is relied upon to maintain the element central within the pocket, whereas in Figs. 5, 6, 7 and 8 I have shown additional supporting means varying slightly in construction but each designed to prevent displacement of the wire coil, yet shaped to insure heating by the electric current passing therethrough. For instance in Fig. 5 I have shown an inner tube 19 which is positioned in the body and the wound wire ignition element 12 is positioned therein and supported by its peripheral surface engaging the inner cylindrical side walls of the shell in a way to prevent it from unwinding or otherwise becoming displaced.

In Fig. 6 the element is shown tightly wound on a suspended high temperature insulator 15' positioned central within the pocket.

Fig. 7 shows somewhat the same construction except that the suspended insulator 15' is of preferably smaller diameter than the coil and whereby the coil is not in direct contact with said insulator which is designed to act as a support only in case of deformation of the coil. Another form of construction would be to use a wire with a high temperature enamel or porcelain insulation wound in coil form as shown in Fig. 8 in which case the enamel covering would act as a protection to the wire 12 and keep it from contacting with the igniting gases and accidental contact with the body. Other methods of preserving the shape or form of the ignition element may obviously be resorted to. Any metal, alloy or other material having necessary temperature and electrical properties can be used for the igniting element.

The diagram of a four-cylinder engine shown in Fig. 9 is to show how my element may be connected up in use. In this view 20 represents a cylinder having a piston 40, 10 the ignition plug, 12 the ignition element, 21 an ordinary storage battery and 22 switch for manually making and breaking the circuit. All four ignition elements are connected in parallel so that in case of failure of one it would not affect the operation of the others. The charging generator 26 is connected to the crank shaft 23 of the engine by means of the gears 24 and 25 and is

driven thereby. A circuit connection 28 is placed between the generator terminal 27 and a point in the igniter circuit intermediate the battery and the switch terminal 31.

5 An automatic cutout 29 of the usual type is interposed in the circuit 28 to prevent back discharge from the battery into the dynamo electric machine.

An additional feature of control if desired would be the insertion of a variable resistance in the circuit between the battery and the plugs whereby the time of ignition could be retarded by decreasing the voltage on the element by manual control.

15 Having thus described my invention, what I claim and desire to secure by Letters Patent, is:

1. An ignition device for a variable speed internal combustion engine consisting of an ignition element adapted to be heated by low voltage current, and means for causing a variation in temperature at different points of said ignition element.

2. An ignition device for a variable speed internal combustion engines consisting of an ignition element adapted to be heated by a low voltage current, and means for diminishing the temperature of one part of said element over that of the other parts of the element, the length heated to ignition temperature depending on the voltage supplied.

3. An ignition device for a variable speed internal combustion engine consisting of an ignition element adapted to be heated by a low voltage current, and means for diminishing the temperature of one part of said element over that of the other parts of the element, the section heated to ignition temperature depending on voltage supplied.

4. An ignition device for variable speed internal combustion engines consisting of a receptacle, a heating unit having portions adapted to be heated to different temperatures for automatically igniting a charge in the receptacle, means for supporting the unit in said receptacle, and means for varying the temperature in the portions of said unit with the speed of the engine.

5. An ignition device for variable speed internal combustion engines consisting of a heating unit adapted to ignite a charge in the engine, and means depending on the voltage across the terminals of said heating unit for advancing automatically the point of ignition of said device in accordance with the speed of the engine.

6. An ignition device for a variable speed internal combustion engine, consisting of a heating unit so arranged that at certain voltage a definite zone is heated and as voltage is increased due to speed of a variable speed engine that another zone of the heating unit is heated.

7. An ignition device for a variable speed

internal combustion engine, consisting of a heating unit so arranged that at a certain voltage one portion is heated and at an increased voltage an adjoining portion is heated, and at a still higher voltage the entire element is heated.

8. An ignition device for a variable speed internal combustion engine, consisting of a heating unit so constructed and arranged as to afford less resistance to electric current at one end than the other and thereby susceptible of being heated throughout its length beginning first at one end and gradually heating through to the other end.

9. An ignition device for a variable speed internal combustion engine, consisting of a body having an elongated pocket formed therein, a heating unit arranged longitudinally in said pocket so that at certain voltage the inner end is heated and as voltage is increased due to speed of a variable speed engine that another zone of the heating unit is heated.

10. An ignition device for a variable speed internal combustion engine, consisting of a heating unit comprising an elongated wire coil, the windings at one end of which are closer together at one end than the other so that at a certain voltage one portion is heated and at an increased voltage an adjoining portion is heated, and at a still higher voltage the entire element is heated.

11. An ignition device for a variable speed internal combustion engine, consisting of an elongated heating unit, susceptible of being gradually heated throughout its length, one portion being more open to radiate than the remainder of said unit.

12. An ignition device adapted to fire a charge in an internal combustion engine, comprising an ignition element in the form of a single piece of coiled wire adapted to be heated throughout its length by an electric current passing therethrough, the individual convolutions of said coil being so positioned relative to each other that radiation progresses with varying rapidity throughout the coil.

13. An ignition device for a variable speed internal combustion engine consisting of a heating unit of coiled wires susceptible of being gradually heated throughout its length, the number of coils in said unit along the axis thereof being greater per unit length of axis at one end than at the other.

14. An ignition device adapted to fire a charge in an internal combustion engine, comprising an ignition coil in the form of a single piece of coiled wire adapted to be heated throughout its length by an electric current forced therethrough, a casing for said ignition element, supporting means for said coil, the individual convolutions of said coil being so positioned relative to each

other and to the casing that radiation progresses with varying rapidity throughout the same.

15. An ignition device for a variable speed internal combustion engine, consisting of an ignition element adapted to be heated by a low voltage current, a casing surrounding said element, means for supporting said element in the casing, said element comprising a length of coiled wire having convolutions positioned closer relatively at the outer end than at the inner end.

16. An ignition device for a variable speed internal combustion engine, including an ignition element adapted to be heated by an electric current, a casing for said element, means for supporting said element in said casing, said element consisting in the length of wire coiled in conical formation, the convolutions at the base of said coil being more widely separated than at the apex thereof.

17. An ignition device for a variable speed internal combustion engine consisting of an ignition element adapted to be heated by low voltage current, means for causing a variation in temperature at different points of said ignition element, and means for preventing displacement of the ignition element.

18. An ignition device for a variable speed internal combustion engine consisting of an ignition element adapted to be heated by low voltage current, means for causing a variation in temperature at different points of said ignition element, and means positioned centrally of said coil for preventing lateral displacement thereof.

19. In ignition means for explosion cylinders of variable speed internal combustion engines, the combination of a casing open to said cylinder, a heating unit in said casing, and a plurality of means for heating said unit, one of said means being effective to heat the coil when the other heating means are inoperative, and another of said heating means varying in heating effect with engine speed.

20. In an ignition means for cylinders of gas engines, the combination of a casing open to said cylinder, a heating unit in the casing having connected portions adapted

to be heated to different temperatures, and separate means for heating the portions of said unit.

21. In an ignition means for cylinders of gas engines, the combination of a casing open to said cylinder, a heating unit in the casing having interconnected portions adapted to be heated at different rates, and separate means including a dynamo electric machine for heating said interconnected portions.

22. In an ignition means for cylinders of gas engines, the combination of a casing open to said cylinder, a heating unit in the casing having portions adapted to be heated at different rates, a dynamo electric machine connected to said unit, and a battery also connected to said unit, said dynamo electric machine and battery being adapted to supply current to the heating unit independently of each other.

23. In an ignition system for internal combustion engines, having combustion cylinders, the combination of a dynamo electric machine, a storage battery adapted to receive current from said dynamo electric machine, a heating coil positioned in a cylinder of said engine, circuit connecting said coil, battery and dynamo electric machine, said circuit being normally closed to maintain the coil in heated condition and mechanical means connecting the dynamo and engine whereby the dynamo speed in voltage varies with that of the engine.

24. In an ignition system for internal combustion engines having combustion cylinders, means for igniting the charges in said cylinders comprising a storage battery, a dynamo electric machine adapted to supply current from the battery to start the engine and to supply current to the battery after the engine is operating under its own power, a heating coil in the cylinders of said engine, circuits normally connecting the dynamo electric machine, storage battery and coil to maintain the coil in heated condition and mechanical means connecting the dynamo and engine whereby the dynamo voltage varies with that of the engine speed.

Signed at Bridgeport in the county of Fairfield and State of Connecticut this 26th day of July, A. D., 1921.

JOHN ALLEN HEANY.
